UNITED STATES PATENT OFFICE.

EUGÉNE FRANÇOIS SUTER, OF LONDON, ENGLAND.

ELECTRICAL HEATING APPARATUS FOR PERMANENTLY WAVING HAIR.

1,266,879.

Specification of Letters Patent.

Patented May 21, 1918.

Application filed August 6, 1917. Serial No. 184,765.

To all whom it may concern:

Be it known that I, EUGÉNE FRANÇOIS SUTER, residing at London, England, have invented certain new and useful Improvements in Electrical Heating Apparatus for Permanently Waving Hair, of which the following is a specification.

My invention relates to an improved electrical heater for use in dressing natural hair on the head, so as to permanently wave the same. For this purpose the hair is done up into tightly wound coils on a suitable curler, damped with a borax or other preferred solution or preparation and inclosed 10 in stiff paper tubes; a tubular electric heater being then applied to the same. As however the hair is coarser and more abundant near the roots, that portion requires to be heated for a longer period than toward the 20 tips, where the hair is finer and easily injured by excessive heat, thus rendering it impossible to obtain perfect results by uniformly heating the hair throughout its length, as practised with the heaters hitherto 25 employed.

My invention has for its object to provide an improved electrical heater constructed and arranged so that the heat can be applied to and distributed over the different parts of the coiled hair as required.

To effect this according to my present invention an electrical heating apparatus for such purposes comprises two or more independent heaters or heating sections 35 which are connected to and controlled by a suitable switch so that such independent heaters or sections may be cut into or out of circuit as required, independently of the other or others.

The independent heaters or heating sections are of the usual tubular construction, and are spaced apart and arranged co-axially by means of struts or the like, to prevent heat passing from one heater to 40 the other. The switch, whereby the operation of such independent heaters is controlled, is preferably of a tubular form and disposed co-axially with and separated from the heaters by struts or the like, so as to 45 avoid the heating of such switch when the apparatus is in use.

My invention is illustrated by way of example in the accompanying drawings wherein similar reference numerals indicate corresponding parts.

Figure 1, is an external view, and Fig.

2, a longitudinal sectional view of a convenient form of electrical heating apparatus adapted for use in permanently waving hair, made in accordance with my present 60 invention.

Fig. 3, is a sectional view on the line A—A, Fig. 2.

Fig. 4, is an end view of the switch shown in Figs. 1 and 2, with the cover plate removed, and partly in section to show the construction, while Fig. 5, is a diagram illustrating the electrical connections of the independent heaters and switch, shown in the preceding views.

1 and 2, indicate the independent electrical heaters or heating sections, and 3, the switch. Such heaters and switch are arranged co-axially, and are separated and secured in position by the tubular struts 4 70 and 5, respectively, which struts form air gaps as illustrated, to prevent heat passing from one heater to the other, or from the heater 2, to the switch.

Each of the heaters 1 and 2, is of the usual 80 tubular construction, and comprises a tubular casing, equipped in any suitable manner with a heating resistance 6, that is insulated from the inner walls of its casing by a layer of mica, or the like, 7, and is covered with 85 asbestos or other suitable insulating material 8, to prevent heat escaping to the outside of the casing.

The switch 3, is tubular in form and may be of any suitable design. As shown the 90 switch comprises a tubular block 9, of ebonite or the like, which is furnished with insulated cover plates 10, secured thereto in any convenient manner, and carries a fixed contact 11, and a pivoted contact 12, that 95 works on the pin 12^a, and carries an operating lever 12^b, the block 9, being also perforated so as to afford ways for the conductors, as indicated at 13, Fig. 4.

In the construction illustrated, the heater 100 1, is connected directly to the flexible main leads 14, secured in the switch 3, by the conductors 15, 15^a, see Fig. 5, while the heater 2, is connected in parallel through the switch 3, by the conductors 16, such conductors being led to the heaters through the adjacent struts 4 and 5, from which they are suitably insulated.

The heater 1, is arranged at the forward end of the apparatus so that it serves to 110 heat the thicker portion of the coiled hair toward the roots, and is brought into use

when the main leads 14, are connected by a plug, or other convenient means, not indicated in the drawings, with a suitable source of current, while the heater 2, remains out of use until the switch 3, is closed. The heater 2, is arranged so as to apply heat to the finer parts of the hair more remote from the roots, and can be cut into and out of operation as often as required, by means of the switch 3, quite independently of the heater 1.

Such improved electrical heating apparatus may be conveniently suspended ready for use, from a counterweighted cord that works over a suitable pulley, and is attached 15 to the eye 17, on the switch, as indicated in Fig. 1.

By my improved construction and arrangement of electrical heating apparatus for use in dressing hair, the application and 20 distribution of heat to the hair under treatment, can be controlled as required, so that all risk of injuring the hair by overheating one part in order to effectively treat the other, is avoided. My improved apparatus 25 is also very effective for re-waving permanently waved hair, of which only the new growth near the roots requires treatment, for which purpose the front heater 1, is used alone.

I claim as new and desire to secure by Letters Patent:

1. In electrical heating apparatus adapted for use in permanently waving hair, a plurality of independent tubular heaters arranged along a common axis so as to be heat insulated from each other, and in combination with a switch whereby one of such heaters may be put into and out of operation independently.

2. An electrical heating apparatus adapted for use in permanently waving hair, comprising a plurality of independent tubular heaters and a tubular switch spaced apart and arranged co-axially by means of struts and having electrical connections arranged 45 so that one of said heaters may be independently put into and out of operation.

3. An electrical heating apparatus adapted for use in permanently waving hair comprising two independent tubular heaters and a tubular switch spaced apart and arranged coaxially by hollow struts, electrical connections forming a main circuit adapted for connection to a source of current and also a sub-circuit controlled by said switch so that 55 one of said heaters can be independently put into or out of operation as required.

EUGÈNE FRANÇOIS SUTER.
